UNITED STATES PATENT OFFICE.

CHARLES EYSTER, OF HOLCOMB, ILLINOIS.

SAFE OR VAULT.

SPECIFICATION forming part of Letters Patent No. 623,145, dated April 18, 1899.

Application filed April 11, 1898. Serial No. 677,264. (No model.)

To all whom it may concern:

Be it known that I, CHARLES EYSTER, a citizen of the United States, residing at Holcomb, in the county of Ogle and State of Illinois, 5 have invented certain new and useful Improvements in Safe and Vault Protection, of which the following is a specification.

The object of this invention is to form a protection for safes and vaults in which the 10 door of the safe or vault is connected to the door of the protection in order that in securing the safe or vault door in a closed position will also hold the door of the protection closed, the bolts and combination of the safe or vault 15 door operated from the outside of the door of the protection except in instances where the time-movement automatically moves the bolts.

In the accompanying drawings, Figure 1 is 20 a horizontal section of a safe and my improved protection in which the doors are closed. Fig. 2 is a similar view in which the doors are partially opened. Fig. 3 is a vertical section through the dial arrangement of 25 the combination. Fig. 4 is a horizontal section through the dial connection of the protection-door. Fig. 5 is a horizontal section through the dial combination of the safe or vault door. Fig. 6 is a horizontal section 30 through the link connection between the two doors, showing the construction of its connection with the safe or vault door. Fig. 7 is a vertical section through the link connection between the two doors, showing the construction 35 of its connection with the door of the protection.

The safe 1 represented in the drawings is of the ordinary construction, having the hinged door 2, a combination-knob 3, and a 40 bolt-throwing lever 4.

The protection surrounding the safe consists of the bottom 5, sides 6, back 7, front 8, top 9, and hinged door 10. The hinged door has an ordinary combination knob and dial 45 11 and bolt-throwing lever 12.

To the outer face of the safe-door 2 is secured a catch composed of the base-plate 13 and central stud 14, supported between the plates 15. The stud is located in a vertical 50 position. To the inner face of the door to the protection is secured a bracket 16, pivotally

supporting a bar 17, having its free end 18 in hook form.

At Figs. 3, 4, and 5 I have shown an arrangement for forming a connection between the 55 dial of the safe and protection doors. The spindle 19 of the dial of the protection-door extends through the door and supports a knob 20, having a radial opening 21. The knob of the dial arrangement connected to the safe- 60 door has a like radial opening 22. Link 23 has its ends 24 made to conform to the surface of the knobs 3 and 20 and provided with studs 25, their free ends supporting spring-catches 26. A similar link 27 forms a connection between the bolt-throwing levers 4 and 12 of the safe and protection doors. The pivotal points of the bar 17 and links 23 and 27 are the same distance from the faces of the 65 doors as the hinged connection of the doors 70 in order that both doors can swing while the bar and links are in connection with the doors, thus producing a parallel motion.

In connecting the bar with the safe-door both doors are opened sufficiently to allow the 75 hooked end 18 of the bar 17 to surround the pin 14, as shown in solid lines, Fig. 6, and when the doors are closed the catch will have embraced the hooked end of the bar and will be in the position shown in dotted lines, Fig. 80 6, which prevents its disengagement while the doors are in their closed position, thereby forming a connection between the doors, so that when the safe-door is locked in its closed 85 position the protection-door will also be held closed.

After the connection is formed between the doors by the bar 17 the link 23 is placed in connection with the combination-knobs, as 90 shown at Fig. 3. The spring-catches will prevent the disengagement of the link. A similar connection is formed by the link 27 between the bolt-throwing levers. The protection-door is then closed, which will close the safe-door, and by means of the knob 12, 95 through the link 27, the bolts of the safe are thrown, and by means of the knob 11 the combination is thrown off, thereby securely locking the safe and protection doors. The reverse movement of the operative parts will 100 release the safe-door, when both doors can be opened, and if desirable the bar and link can

be disconnected from the safe-door, and during business hours the safe-door can be opened and closed independent of the protection-door.

5 The object of this protection is to form an air-space around the safe, which will be of great service in saving the contents of the safe in case of fire and will present an additional barrier to the operation of burglars, 10 as it would be impossible for them to use explosives, as the protection is not designed to have tight joints.

It is evident that the same arrangement of connection between the outer casing and 15 vault-doors could be arranged.

In some arrangements of safe and vault doors a combination is not employed. A time-movement controls the operation of the bolts in such instances.

20 I claim as my invention—

1. In a protection for safes and vaults, the combination of a safe or vault door, and a door of an outer casing having a connection through the medium of a pivoted bar, a bolt- 25 throwing knob for each door, a link connecting the knobs, a combination-knob for each door and a link connecting the knobs.

2. In a protection for safes and vaults, the combination of a safe or vault door, and a 30 door of an outer casing, a bar having a piv-

otal connection with one of the doors and a detachable connection with the other door, the detachable connection consisting of a bracket supporting a vertical stud and the end of this bar being in hook form adapted 35 to interlock with the stud.

3. In a protection for safes and vaults, the combination of a safe or vault door, and a door of an outer casing, a bolt-throwing lever for the safe or vault door, a corresponding 40 lever connected with the outer casing, a rod connecting the levers, and a connection between the doors through the medium of a pivoted bar whereby the bolt-works of the safe or vault door are manipulated from outside 45 the casing.

4. In a protection for safes and vaults, the combination of a safe or vault door and a door of an outer casing, a combination-dial for the safe or vault door, a corresponding 50 dial connected with the outer casing, a rod connecting the dials and a connection between the doors through the medium of a pivoted bar whereby the combination of the safe or vault door is manipulated from outside the 55 casing.

CHARLES EYSTER.
